UNITED STATES PATENT OFFICE

KARL S. HOWARD AND EDWIN C. JACKSON, OF ST. LOUIS, MISSOURI, ASSIGNEES, BY MESNE ASSIGNMENTS, TO GENERAL STEEL CASTINGS CORPORATION, OF GRANITE CITY, ILLINOIS, A CORPORATION OF DELAWARE

LOCOMOTIVE STRUCTURE

Application filed June 5, 1929. Serial No. 368,509.

Our invention relates to railway rolling stock and consists in a novel framing structure particularly adapted for use in railway locomotives.

5 A locomotive usually includes a plurality of pumps for water and air and cylinders with pistons operated by compressed air for actuating the brakes, etc. Heretofore these pump bodies and air brake cylinders have been completed separately from the locomotive structure and have been provided with brackets by which they may be secured to the locomotive framing, etc. The locomotive structure has also included brackets or other 10 provision for the mounting of the pumps and cylinders, etc., and this construction has necessitated a great deal of machining, for the purpose of fitting the parts together, drilling, for the purpose of providing holes for 15 securing bolts and rivets, and frequent inspection of the assembled structure to insure the maintenance of the proper assembly. Frequently the securing elements are not readily accessible and can only be inspected 20 and tightened with difficulty.

It is the main object of our invention to eliminate the above mentioned disadvantages of the usual structure by forming brake cylinders and the bodies of air compressors, and 25 water pumps, etc. integrally with the framing of the locomotive whereby a fixed relation between the parts will be maintained and inspection of the same and tightening of securing elements can be avoided.

30 We also desire to utilize the brake cylinders for bracing the framing structures and thereby eliminate the use of many bracing members previously required which served no other purpose.

35 Another object of our invention is to form the inner heads of the pump cylinders and either the pressure head or non-pressure head and spring housing of brake cylinders integral with the cylinder bodies and the framing of the locomotive.

40 Another object of our invention is to form the steam, air, and water passages, and valve chamber integrally with the pump cylinder and the framing of the locomotive.

45 The cylinders, cylinder heads, passages etc.

can be formed integrally with the framing of the locomotive by casting or by any combination of the methods of casting, welding, forging, machining, etc.

In the accompanying drawings which illustrate our invention—

55 Figure 1 is a top view of one longitudinal half of a locomotive bed or underframing which includes as an integral part thereof cylinders and pump structure as referred to above.

Figure 2 is a side elevation of the structure shown in Figure 1.

60 Figure 3 is an enlarged side view of the forward portion of the frame shown in Figures 1 and 2 and includes a vertical longitudinal section taken substantially on the line 3—3 of Figure 1.

65 Figure 4 is a horizontal section taken substantially on the line 4—4 of Figures 3 and 6.

70 Figure 5 is a front elevation of the structure.

75 Figure 6 is a side view and section corresponding to Figure 3 but illustrating the structure on the opposite side of the locomotive.

Figures 7 and 16 are horizontal sections taken on the corresponding section lines of Figure 3.

80 Figures 8, 11, 12 and 13 are similar sections taken on the corresponding section lines of Figure 6.

85 Figures 9, 10, 14 and 15 are vertical transverse sections taken on the corresponding section lines of Figure 2.

88 Figures 17 and 18 are vertical transverse sections taken on lines 17—17 and 18—18 of Figure 3.

90 Figure 19 is a top view of a portion of a framing embodying a modification of our invention.

Figure 20 is a side elevation of the same structure.

95 Figure 21 is a vertical section taken on the line 21—21 of Figure 20.

100 Preferably, our invention is embodied in a one-piece locomotive bed or underframe which may consist of a single casting or may be formed by welding together into an integral whole one or more framing members.

and the cylinder and pump parts. In the illustrations shown in the drawings, the side frames of the bed are indicated at 1, each having integral pedestal-forming portions 2 and united with the corresponding side frame on the opposite side of the locomotive by horizontal webs 3 and 4 provided with suitable openings 5 to lighten the structure and also to provide access to the interior of the bed, if necessary. The steam cylinders 6, steam supply chambers 7, boiler saddle 8, front deck 9, buffer 10, valve gear brackets 11, brake hanger lugs 12, and equalizer fulcrums 13 and various other parts are also formed integrally with the framing and greatly reduce the amount of machining and assembling labor and the number of elements otherwise required for securing the various parts to the framing. Formed integrally with the side frames in front of the cylinder and boiler saddle on the near side of the locomotive are cylindrical chambers 14, 15, 16 and 17, the same comprising, respectively, high pressure air, low pressure steam, low pressure air, and high pressure steam cylinders of the air pump. On the far side of the locomotive are similar integrally formed cylindrical bodies 18, 19, 20 and 21 forming the water and steam cylinders of a two cylinder feed water pump, the lower cylinders being the water cylinders and the upper cylinders being the steam cylinders.

Each of the elements 14 to 21, inclusive, has its inner head formed integrally with its body and is provided with a detachable outer head which may be secured to the body in the usual manner. All of the elements 14 to 21 are integral with the front portion of the bed and with each other and are provided with suitable braces, such as indicated at 22, also formed integrally with the framing and the pump bodies. All of these pump parts have their axes disposed vertically and may be machined on a suitable machine with the assurance that when they are once completed their alignment and other relations with each other will be maintained throughout the life of the locomotive. If desired, the cylinders 14 to 21 may be provided with renewable bushings of brass, Monel or other metal as is common practice in cylinder construction.

Preferably, each of the steam chambers 15 and 19 has an integral exhaust steam passageway 23 and 24, respectively, connecting it to the adjacent exhaust steam passage 25 leading from the adjacent main steam supply chamber 7 to the exhaust stack which will be mounted over the opening 26 in the boiler saddle.

Similarly, the steam passages 27 between cylinders 15 and 17, passage 28 between cylinders 19 and 21, and passage 28a on the left hand side of cylinder 21 will be formed integrally with the cylinders, by means of

suitable coring, during the casting operation. These passageways carry the steam to or from the cylinders according to the direction of movement of the pistons.

The cylinders 14 to 17 comprising the air pump structure are arranged in sequence so that the steam used in the high pressure cylinder 17 is discharged into the low pressure cylinder chamber or body 15 and the air compressed in the low pressure cylinder 16 is discharged through passageway 29 into the high pressure cylinder 14.

Detachable outer heads 30 and 31 are provided for the cylinders and the upper head 30 will include suitable valve structure for controlling the steam admitted through pipe 32 to passage 33 formed integrally with the cylinder wall. Lower head 31 will include an air inlet 34, valve chamber, valves, and a passageway leading from cylinder 16 to cylinder 14. Air inlet passageway 35 and valve chamber 35a is provided in the cylinder structure and integral therewith. Outlet air passageway 35b and valve chambers 35c are provided integral with cylinder 14.

The feed water pump structure comprises two pumps, each receiving steam from supply lines 36 through passageways 36a integral with cylinders 19 and 21 independently of the other pump and each receiving water through supply line 37 and respective individual water valve chambers 42 integral with cylinders 18 and 20 and independently of the other pump and each discharging water through its valve chamber to a common discharge line 39. The water valve chambers 42 are connected by an integral passageway 45 (Fig. 13) on the inlet side and by an integral passageway 46 (see Fig. 11) on the outlet side. Passageways 42a connect each water cylinder with each valve chamber 42. A suction air chamber 38 integral with and between the upper steam cylinders 19 and 21 and the lower water cylinders 18 and 20 is connected with supply valve passageway 45 by means of passageway 44 and serves to equalize the pressure and prevent pounding in the water inlet pipe 37. A separately formed head 40 is applied to the steam cylinders 19 and 21 and includes suitable valves 41 by which the steam is distributed to the opposite sides of the piston heads 47. Lower cylinder heads 43 are formed separately and applied to the bodies of cylinders 18 and 20. The pump structure per se forms no part of our present invention and is well-known in the art as the Elesco pump. Exhaust steam passageways 24a are integral with cylinders 19 and 21 and connect with the passageway 24.

A shield 48 is located in front of each pump structure and preferably is formed integrally with the deck plate 9 and buffer beam 10 and has a general U-shaped section horizontally disposed whereby its rigidity is maintained

and, on the feed water pump side, the outer water valves are substantially enclosed by the corresponding shield.

At the rear of the boiler saddle and main steam cylinder structure, I provide a series of 5 brake operating cylinders 50, 51, 52 and 53, each of the cylinders 51 and 52 being located intermediate the side frames 1 with its axis disposed vertically. The side walls of these 10 vertically disposed cylinders merge with the horizontal webs 3 and 4, cooperating with the latter to form a rigid brace between the spaced side members. Preferably, one of the ends of each cylinder is formed integrally with the remainder of the cylinder and bed structure. Cylinder 51 has its lower or non-pressure head 51a formed integrally and including a housing 54 for the release spring 55, (Fig. 14).

20 Horizontally disposed cylinder 53 (Fig. 2) is shown without either end or head being formed integrally therewith, the heads being applied in the usual manner. This arrangement may be embodied in any of the cylinders. 25 Cylinder 52 (Fig. 15) is shown with its pressure head or upper head 56 formed integrally and the lower or non-pressure head 57 being applied in the usual manner.

The pedestal-forming portions 2 on opposite sides of the bed are connected by suitable braces 58 and these braces extend a substantial distance below and to the side of the adjacent air brake cylinders and are spaced from web 4 so as to facilitate the molding of 30 the cylinders and avoid interference with the operation of the pistons in the cylinders and with the levers connected to the pistons.

Cylinders 50 (Fig. 2) are disposed with 40 their axes horizontal and are arranged side by side and partially located in a depression formed in the top member 3 of the bed (Fig. 10). The rear heads or ends of cylinders 50 are in line with and form part of a continuous transverse vertical wall 59 extending 45 from side to side of the bed and the outer ends of which form brackets 60 on which the valve gear mechanism (not shown) may be mounted. Obviously, this cylinder structure braces the adjacent parts of the bed and, obviously, the integral formation of the cylinder side framing eliminates the necessity of machining numerous surfaces on separately formed cylinders and the machining of suitable supporting brackets on the frame 50 and the provision of a multitude of attaching bolts or rivets. Moreover, the cylinders will always be rigid and will not require any inspection or tightening of elements in order to maintain their assembly with the bed structure.

60 Each of the brake cylinders 50 forms part of an individual brake mechanism for a front driving wheel on a corresponding side of the locomotive as shown by the brake lever 65, pull rod 66, and brake head 67. Likewise,

each of the brake cylinders 53 forms part of an individual brake mechanism for a rear driving wheel on a corresponding side as shown by the brake lever 68, pull rod 69, and brake head 70. The brake cylinders 51 and 52 form parts of an individual brake mechanism for each pair of intermediate driving wheels as shown by brake lever 71, pull rod 72 and brake head 73. The brake levers 65, 68 and 71 are fulcrumed in brackets 74 which 75 are cast integral with the locomotive bed.

It is to be understood that our invention is not to be limited to this arrangement of brake cylinder and brake mechanism, but includes arrangements where either one or more of the 80 above brake cylinders are omitted and where one or more pairs of wheels are controlled by the same brake mechanism, or where all of the driving wheels or all of the driving wheels on each side are controlled by the 85 same brake mechanism, or where each driving wheel is controlled by an individual brake mechanism.

In Figures 19 to 21 we illustrate a modification in which the two forward cylinders 90 61 are disposed vertically with their side walls 62 merging with the inner vertical walls 63 of the bed side frame. In this construction, the cylinder will not be directly connected with the valve gear bracket 64 95 but, nevertheless, will serve to brace the bed structure adjacent and in addition to the valve gear bracket.

While we prefer to form the entire structure described in a single casting, we consider the welding together of two or more units to complete the structure as being within the spirit of our invention. Nor is it necessary to form the entire bed in an integral structure. A separate cradle structure or a 100 separate front end member could include the integral brake cylinder structure which is the gist of our invention. In any form, the objects stated in the forepart of this specification are attained with a marked degree of 105 success.

Many other details of our construction may be modified without departing from the spirit of our invention and we contemplate the exclusive use of such variations as come within 110 the scope of our claims.

We claim:

1. In a locomotive, spaced side frame members forming opposite sides of a brake cylinder body. 120
2. In locomotive framing, spaced frame members, a transverse web extending between said members, a brake cylinder body, and a head for said cylinder extending substantially in line with said web and integral therewith. 125
3. In a locomotive framing, spaced frame members, a vertically disposed brake operating cylinder structure located between said members and integral therewith, and spaced 130

- horizontal webs connecting said cylinder structure and said members and forming with said cylinder a series of box shaped sections between said members.
5. In locomotive framing, spaced frame members, a brake operating cylinder structure integral with said members and forming a brace between the upper portions of said members, and a transverse member between the lower portions of said members spaced from and unconnected with said cylinder structure except through said side members.
10. In locomotive framing, spaced frame members, a brake operating cylinder structure integral with said members and forming a brace between the upper portions of said members, and including a downwardly directed release spring housing, and a transverse member extending downwardly from said side members and then transversely of the framing and spaced from said housing.
15. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
20. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
25. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
30. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
35. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
40. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
45. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
50. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
55. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
60. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
65. In locomotive framing, spaced frame members having pedestal forming elements on their lower portions, a box shaped center member, brake cylinder structure formed as a part of said center member, a transverse member spaced below said center member and connected to said elements and to the sides of said center member, all of said parts forming a one piece structure.
70. A locomotive framing structure having high and low air compressor cylinders, a head for each of said cylinders, a valve chamber for each cylinder and an air passageway connecting both cylinders, all formed integrally.
75. A locomotive front deck plate having a pump body and pump valve chamber integral therewith.
80. In combination, a locomotive frame structure, a plurality of pump bodies and motive fluid chambers for operating the pumps, all integral with each other.
85. In combination, a locomotive framing structure, a plurality of pump bodies, individual pump valve chambers spaced from each other, a fluid inlet, and a fluid passageway connecting said valve chambers and said inlet, all formed integrally with each other.
90. In a locomotive structure, a frame member, a supply chamber for the engine cylinders and having a main steam exhaust passage, a water pump body, a steam cylinder for operating the water pump, and an exhaust passage leading from said steam cylinder to said main exhaust steam passage, all of said parts being integral with each other.
95. In a locomotive structure, a frame member, a supply chamber for the engine cylinders and having a main steam exhaust passage, a water pump body, a steam cylinder for operating the water pump, and an exhaust passage leading from said steam cylinder to said main exhaust steam passage, all of said parts being integral with each other.
100. In a locomotive structure, a steam supply chamber for an engine cylinder and having an exhaust steam passageway, a steam pump cylinder formed integrally with said chamber, and an exhaust steam passageway leading from said pump cylinder to said main exhaust steam passageway and integral therewith.
105. In a locomotive underframe, a main frame member, a main steam supply chamber, high compression and low compression chambers for an air compressor, high compression and low compression cylinders for steam pumps for said compressor chambers, and exhaust steam passageways for said cylinders and said main steam supply chamber, all formed integrally.
110. In a locomotive framing structure, a frame member, an air compressor cylinder, air pump steam cylinder in alignment with said compressor cylinder, inner heads for said cylinders, and a brace extending between said cylinders and member, all formed integrally.
115. In a locomotive underframe structure including a cylinder saddle and a side frame member, and an air compressor cylinder integral with the portion of said member in front of said saddle.
120. In a locomotive underframe structure including a cylinder saddle and a side frame member, and an air compressor cylinder integral with the portion of said member in front of said saddle.
125. In a locomotive underframe structure including a cylinder saddle and a side frame member, and a water pump cylinder integral with the portion of said member in front of said saddle.
130. In a locomotive underframe structure including a cylinder saddle and a side frame member, and a water pump cylinder integral with the portion of said member in front of said saddle.

cluding a cylinder saddle and side frame members, an air compressor cylinder, a water pump, and motive fluid cylinders for operating said pump and compressor, said cylinders, pump, and compressor being positioned in front of said saddle and integral with said side frame members and positioned vertically relative thereto.

27. In a locomotive underframe integral structure, a plurality of pump bodies, an inlet and an outlet valve housing for each body, an inlet passage leading to one of said inlet housings, an outlet passage leading from one of said outlet valve housings, and passages connecting said inlet valve housings and said outlet valve housings, respectively.
28. A locomotive bed including side frame elements, a transverse member forming a guide yoke support, and a brake cylinder integral with said member.
29. In a locomotive structure, a frame cross tie element having a guide yoke plate and bracket and a brake cylinder integral therewith.
30. In a locomotive, an integral structure including a front deck plate, a pump body extending sidewardly therefrom, and a brace extending between said body and plate.

In testimony whereof we hereunto affix
our signatures this 7th day of May, 1929.

KARL S. HOWARD.
EDWIN C. JACKSON.
